TYPEWRITING MACHINE

William A. Dobson, Wethersfield, Conn., assignor to Underwood Elliott Fisher Company, New York, N. Y., a corporation of Delaware

Application May 2, 1938, Serial No. 205,455

8 Claims. (Cl. 197—114)

This invention relates to selective line-spacing mechanisms for typewriting machines.

The invention has for its general object the provision of a line-spacing mechanism of simple and rugged construction, assuring dependable service, the mechanism including a line-space-selector device which facilitates the manual setting of the mechanism to effect the desired line-spacing.

In its more specific embodiment, the invention provides an improved line-space-selector device including a pawl-throw control arm adapted for fabrication in a single piece and having an overthrow or toggle spring, and detent means cooperating with the control arm, each capable of manufacture in simple form, presenting a conveniently settable device for controlling the extent of line-space rotation of the typewriter platen.

In use, the control arm is position-adjustable to either of a plurality of settings, for example, those representing one, two, or three line-space selections, the overthrow spring acting on the control arm to yieldably hold same at either side of a medial position, each eccentric position being defined by an abutment or detent which may include an intermediate recess for yieldably retaining the control arm at the medial position. In each of the mentioned positions, the control arm determines a corresponding action of a ratchet pawl which, upon actuation, moves into engagement with the teeth of a ratchet wheel carried by the platen and causes a rotation thereof to effect the desired line-spacing.

The control arm, by cooperation of the overthrow spring therewith, is yieldably yet forcibly held in either eccentric position from which the control arm may be readily moved to another setting by applying manual pressure on a finger-piece of the arm, sufficient to overcome the power of the overthrow spring. Thus, the operator is relieved from exercising any particular care in setting the mechanism for the desired line-spacing, the control arm and its associated overthrow spring and detent device coacting to permit setting the arm to any line-space-defining position by a simple manipulation, and to forcibly hold the arm at the desired setting.

Other features and advantages will hereinafter appear.

The present invention is in the nature of an improvement of the line-spacing mechanism shown in my Patent No. 1,908,327, issued May 9, 1933.

In the accompanying drawings:

Figure 1 is a perspective view of the line-spacing mechanism, certain of the parts being broken away and showing the mechanism set for triple line-spacing.

Figure 2 is a side elevation of the mechanism, viewing same from a point intermediate the

platen ends, the mechanism being set for triple line-spacing.

Figure 3 is a view similar to Figure 2 but showing the mechanism fully actuated.

Figures 4 and 5 are similar to Figure 2, each showing the mechanism in initial position and showing respectively the setting of the mechanism for effecting double and single line-spacing, and.

Figure 6 shows the mechanism similar to Figure 2 but with the ratchet detent released.

In the drawings, portions of an Underwood typewriter are shown, particularly the related platen carriage thereof, which includes a carriage frame 10 riding on tracks 11 and an end plate 12 secured to the frame 10, upon which is rotatably mounted a platen 13, the shaft 14 of which is journaled in the end plate. A ratchet wheel 15 is mounted to rotate with the platen and has the teeth thereof pitched in line-space distances or increments thereof.

The end plate 12 includes a bracket 16 upon which is swingably mounted, on a stud 17, an arm 18 of a line-space lever 19, the latter having a finger-piece 20 and being preferably pivotally mounted at 21 on the arm 18 as shown and described in my Patent No. 2,107,370, issued February 8, 1938. It will be seen that the arm 18 and lever 19 constitute a bell crank swingable on stud 17 in a horizontal plane to actuate a line-space pawl 22 in a manner hereinafter described to rotate the platen 13 a predetermined degree to effect the desired line-spacing of the work sheet thereon.

The free end of arm 18 has a cylindrical aperture 23 forming a journal for a stud 24 secured to the pawl 22. The stud 24 may rotate freely within the journal 23 and is conical or tapered for a part of its length to also afford a limited 40 but adequate oscillation of same in its journal 23. It will be seen that the journal 23 and the associated stud 24 thus constitute a universal joint by which the pawl 22 is flexibly connected to cooperate with the arm 18 of the line-space lever 19.

The pawl 22 is preferably formed of sheet metal and has a flat body portion on which an ear 25 is bent laterally to carry the stud 24 and provide a broad surface abutting the underside of lever-arm 18. At its free end, pawl 22 has a tooth 26 50 projecting laterally therefrom to overlie the ratchet 15, normally free of the teeth thereof. A pawl-restoring spring 27 engages the pawl at a lug 28 thereof and is anchored to the end-plate 12 as by a post 29, the spring being arranged to pull 55 the pawl forwardly in restoring same to normal quiescent position, as shown in Figures 2, 4 and 5, and with it the associated line-space lever 19 after manual actuation of same. The arrangement of spring 27 is such that same also tends 60

to swing the pawl downwardly to urge pawl tooth 26 toward the ratchet wheel 15.

During actuation, in effecting the desired line-spacing rotation of the platen selectively to a single, double or triple line-space, the pawl moves a uniform distance for any selected line-space. The forward or quiescent position of the pawl 22 may be determined by the arm 18 of lever 19 abutting a shoulder 30 of the end-plate 12, see Figures 1 and 2. In the full actuated position of pawl 22, the pawl tooth 26, after engaging a ratchet tooth, comes against a stop 31 on end-plate 12, the stop face 32 of which is inclined in relation to the direction of approach of pawl tooth 26 so as to cam or wedge same downwardly against the engaged tooth of the ratchet wheel 15 in such manner as to prevent any overthrow of the ratchet wheel as may result from momentum of the platen as same is brought to rest.

The amount of line-spacing is selective, and is controllable by a line-space selector device 35 cooperating with the pawl 22, the selector device including a plate-like arm 36 having a slot 37 preferably open and engaging the platen shaft 14 to provide a swingable and endwise movable mounting for the arm 36, a side of which may lie against the inner face of end-plate 12. Arm 36 is flanged at 38, the flange being stepped to form a shoulder at 39 disposed to engage the bottom edge of the pawl 22. It will be observed in Figure 1, that the flat body portion of the pawl 22 is disposed between and in contact with both the end of a collar 34 adjacent the ratchet wheel 15, and the contiguous portion of the flange 38, the collar 34 and flange 38 jointly forming a guide groove, retaining the forward portion of pawl 22 against excessive lateral displacement although affording ample clearance for same to accommodate the slight lateral oscillation of pawl 22 as required by the arcuate path of stud 24.

By disposing the arm 36 in one of a plurality, preferably three selective positions, the position of arm shoulder 39 so varies the operation of the pawl 22 as to cause same to rotate the platen one, two or three line-spaces, that is, by rotating the ratchet wheel 15 a corresponding number of tooth pitches. By setting arm 36 as shown in Figure 5, for single line-spacing, actuation of the pawl 22 will bring pawl tooth 26 into engagement only with ratchet tooth 15', tooth 26 being caused to pass over the preceding teeth by the action of shoulder 39 with the bottom edge of pawl 22, which edge is formed as a cam to guide tooth 26 in a prescribed path above the ratchet wheel until 55 in position to engage tooth 15'.

In the setting of arm 36 as shown in Figure 4, that is, for double line-spacing, the pawl tooth 26 will be caused to engage ratchet tooth 15' and thus the platen will be rotated two line-spaces. Setting of arm 36 in position shown in Figure 2 will cause pawl tooth 26 to engage the ratchet tooth 15' and thus rotate the platen a distance of three line-spaces.

In each setting of arm 36, the coaction of pawl 22 with shoulder 39 is substantially similar, the pawl, pressed toward the shoulder by spring 27, sliding over the shoulder as the pawl is actuated rearwardly, the pawl tooth 26 being allowed to lower into the appropriate ratchet tooth for rotating the platen the desired line-space degree in accordance with the setting of the line-space selector arm 36.

Arm 36 is extended to provide a finger-piece 40, the arm being offset at 41 to form a shoulder disposed within a slot 42 in the end plate 12, the

finger-piece 40 being thereby disposed at the outside of plate 12 for convenient access by the operator. Slot 42 is arcuately formed substantially concentric with the axis of swing of arm 36, that is, the platen shaft 14, and the offset portion 41 provides a rounded shoulder which, during setting of arm 36, rides along the contiguous edge of slot 42. Thus, slot 42, being of a limited arcuate length, restricts the swing of arm 36 by the abutment of arm portion 41 with the respective ends of the slot, the slot extending either side of a medial position of the arm as shown in Figure 4.

The yieldable retention of arm 36 in position at either extreme of the arc as defined by the limits of slot 42, is effected by a suitable spring, 15 preferably a compression spring or resilient loop 43 having its respective ends articulated to the arm 36 by stud 44, and to a stationary member such as the plate 12 by stud 45. As shown more clearly in Figure 4, the studs 44, 45 are in a line 20 radiating from the axis 14, with the arm 36 in its medial position. It will be seen, therefore, that spring 43, together with a portion of arm 36, constitutes a toggle of which one link, the spring 43, is resilient. The toggle action effected by the 25 resilience of spring 43, urges arm 36 to swing eccentrically of its medial position, that is, toward either extreme of its limited arc, or against either end of the slot 42, as shown respectively in Figures 2 and 5.

The depth of arm slot 37 is such that spring 43 presses arm shoulder 41 against the contiguous edge of slot 42 with the arm in either extreme position, the friction of shoulder 41 on the slot-edge, assisting the spring in resisting movement of the 35 arm 36. At medial position, the slot 42 has a recess or notch 46 into which the rounded shoulder 41 seats, being pressed therein by the action of spring 43 to yieldably retain the arm 36 intermediate the ends of slot 42, see Figure 4.

Accurate detenting of the platen at each typing line is effected by a detent roller 47 cooperating with the teeth of ratchet wheel 15, the roller being carried on an arm 48 pivoted on a stud 49 secured to the plate 12, the mounting of arm 48 to the 45 stud being readily removable by providing a yoke 50 having a U-shaped slot straddling the stud 49. Arm 48 extends laterally at 52, the extending portion being bent around to provide an outer bearing for the roller 47. A spring 53 is seated in 50 a recess in the carriage frame 10 and engages the arm portion 52 to press detent roller 47 into the teeth of ratchet wheel 15, the spring serving also to press arm 48 so as to maintain the yoke 55 in association with stud 49.

For fractional line-spacing, a detent release lever 54 is provided, the same being pivoted on the plate 12 by a stud 55 and having a restoring spring 56 tending to hold lever 54 in ineffective position against a stop 57, as shown in Figure 2, 60 the respective ends of the spring engaging the lever and a fixed member of the platen carriage. The release lever 54 carries a friction shoe 58 swingable into engagement with the free end of a finger 59 of the detent roller arm 48 to wedge 65 the arm by a toggle action so as to retract the roller 47 from the ratchet wheel 15. The friction of the shoe 58 against the end of finger 59, augmented by the pressure of spring 53, latches the parts as shown in Figure 6, against the power 70 of spring 56 until manual actuation of the lever 54 towards stop 57 overcomes the friction to release detent roller arm to normal effective position. Only a slight touch of lever 54, sufficient to overcome the friction, is ample to permit spring 75

56 to swing lever 54 to ineffective position, in which position shoe 58 is entirely free of finger 58 and the latter may therefore move unencumbered during the normal detenting action of 5 arm 48.

The invention is not confined to the exact embodiment shown in the drawings nor to the precise details of construction illustrated therein, but 10 certain modifications and changes may be made within the spirit or scope of the invention as expressed in the appended claims.

I claim:

1. In a variable line-spacing mechanism for 15 typewriting machines, having a pawl and ratchet device and actuating means therefor, in combination, a line-space selector element adapted to control the extent of throw of the pawl, and swingable in a limited arc to either of two pawl-throw determining positions, and a toggle device 20 including a resilient link operatively associated with said element to yieldably hold said element in either position.

2. In a variable line-spacing mechanism for 25 typewriting machines, having a pawl and ratchet device and actuating means therefor, in combination, a line-space selector element adapted to control the extent of throw of the pawl and swingable to either of two pawl-throw determining 30 positions, an overthrow spring cooperating with said element to yieldably hold said element in either position, and a fixed member presenting an arcuate edge substantially concentric with the axis of said selector element, said element including a part pressed by said spring into frictional 35 contact with said edge to assist said overthrow spring in holding said element in either position.

3. In a variable line-spacing mechanism for 40 typewriting machines, having a rotatable platen, a shaft carrying the platen, a carriage member supporting the platen shaft, a pawl and ratchet device for line-space rotation of said platen and actuating means therefor, in combination, an arm 45 adapted to control the extent of throw of the pawl and swingable to either of two pawl-throw determining positions, said carriage member presenting an arcuate edge with abutments at the ends thereof, said arm including an offset shoulder 50 engaging the arcuate edge of said carrying member and limiting the swing of said arm by engaging said abutments, and an overthrow spring cooperating with said arm to yieldably hold the arm shoulder in either abutment engaging position.

4. In a variable line-spacing mechanism for 55 typewriting machines, having a pawl and ratchet device and actuating means therefor, in combination, a line-space selector element adapted to control the extent of throw of the pawl and swingable in a limited arc to either of two pawl-throw determining positions, an overthrow spring 60 cooperating with said element to yieldably hold said element in either position, and means enabling said spring to yieldably retain said element in a third pawl-throw determining position intermediate the two said positions.

5. In a variable line-spacing mechanism for 65 typewriting machines having a rotatable platen, a shaft carrying the platen, a platen-carriage member supporting the shaft, a pawl and ratchet device for line-space rotation of the platen and actuating means therefor, in combination, an

arm adapted to control the extent of throw of the pawl and swingable to a plurality of pawl-throw determining positions, said carriage member having an opening presenting an arcuate edge terminating in abutments at the ends thereof and a notch intermediate the ends, said arm including an offset member engaging the arcuate edge of said carriage member, and an overthrow spring cooperating with said arm to yieldably hold the offset member against either 10 abutment or in the notch, whereby to detent said arm in any selected position.

6. In a variable line-spacing mechanism for 15 typewriting machines having a rotatable platen, a shaft carrying the platen, a ratchet wheel on the platen and a carriage end-member supporting the platen shaft, in combination, a reciprocatory pawl cooperative with the ratchet wheel to rotate the platen in line-spacing, means operative at one end of said pawl for actuating said 20 pawl in uniform extents of stroke, a line-spacing selector arm mounted for swingable and endwise movement on the platen shaft, including an offset shoulder, said pawl having a cam-shaped edge engaging said arm shoulder and cooperating therewith to define different paths for said pawl in accordance with the setting of said arm-shoulder, and means for yieldably holding said arm in one of a plurality of line-space defining positions, said arm being disposed adjacent the ratchet 30 wheel and forming a groove therewith for guiding the free end of said pawl.

7. In a variable line-spacing mechanism for 35 typewriting machines having a rotatable platen, a shaft carrying the platen, a ratchet wheel on the platen and a carriage end-member supporting the shaft, in combination, a reciprocatory pawl cooperative with the ratchet wheel to rotate the platen in line-spacing, means operative at one 40 end of said pawl for actuating said pawl in uniform extents of stroke, a line-spacing selector arm mounted for swingable and endwise movement on the platen shaft, including a shoulder, said pawl having a cam-shaped portion engaging said arm shoulder and cooperating therewith to 45 define different paths for said pawl in accordance with the setting of said arm shoulder, an offset member on said arm, said carriage end-member presenting an arcuate edge engageable by said offset arm-member and having end abutments and an intermediate notch to detent said arm at selective positions, and an overthrow spring pressing said arm toward the arcuate edge and adapted to yieldably hold said arm-member against either abutment or in the notch.

8. In a variable line-spacing mechanism for 55 typewriting machines having a platen carriage, a platen shaft on the carriage and a pawl-and-ratchet device for line-space rotation of the platen, in combination, a control member adapted to regulate the extent of throw of the pawl and pivoted on the platen shaft to swing in a limited arc to a plurality of pawl-throw-determining positions, said control member presenting an operating arm having a finger-piece at its 60 free end, and a compression spring articulated to the carriage at a point farthest remote from the arm pivot and to said arm intermediate the said point and the arm pivot, the points of articulation being on a common line with the arm pivot 65 with said arm in a medial position.

WILLIAM A. DOBSON.
